DEVICE FOR DIVIDING AND
PROPORTIONING LIQUIDS

Roy P. Keammerer, Gary, Ind.

Application June 9, 1941, Serial No. 397,350

5 Claims. (Cl. 202—161)

This invention relates to a device for dividing and proportioning liquids and, particularly, to a device for automatically dividing the condensate during the distillation of a liquid so as to properly proportion the rate of flow of reflux to the rate of flow of product.

In the fractional distillation of liquids, it is customary to condense all of the vapors leaving the top of the column and to divide the stream of condensate into two parts with one part, which is termed "reflux," being returned to the top of the column and the other part, "finished product," being directed to a finished product receiver. In case of either batch distillation or continuous distillation, it is necessary to accurately proportion and control the ratio of reflux and product for the reason that excessive reflux entails a waste of heat energy and reduces the output of finished product, and lack of sufficient reflux results in a product of insufficient purity.

Various devices or means have been heretofore suggested and used for dividing and proportioning the condensate into reflux and finished product in fractional distillation. While some of these proportioning devices or means have been practical and satisfactory in their use, they have been impractical and unsatisfactory in certain respects. For instance, some of the devices heretofore proposed and used included a rotating member having extremely small clearances and which was in contact with the liquid at all times thereby oftentimes resulting in the rotating member becoming frozen in one position, due to corrosion. Such a condition was, of course, unsatisfactory in that it necessitated frequent maintenance and cleaning of the parts and frequently a replacement thereof, which was expensive, as well as inconvenient. Also, in other devices the reflux-product ratios were limited to an extremely narrow range, which was undesirable. When live steam is used in the process of distillation, water is carried along with the vapor issuing forth from the column and follows through with the condensate. If such water is returned to the still column with the reflux, it will decrease the efficiency of the still and, therefore, should be removed from the condensate. Proportioning devices heretofore used had no means incorporated therewith for removing such water from the condensate, which, of course, was another disadvantage of such devices.

In the present invention, there is provided a device for dividing and proportioning the reflux and the finished product wherein all of the above mentioned disadvantages have been eliminated

and, at the same time, a device which eliminates the water from the condensate and the reflux.

Accordingly, it is the general object of the present invention to provide an improved device for proportioning liquids which is simple and inexpensive in its construction and use, and one which is efficient and effective in its use.

It is another object of the invention to provide an improved device for automatically proportioning liquids in which the liquid being divided can be proportioned as desired over a relatively wide range.

It is a further object of this invention to provide an improved device for automatically dividing the condensate in fractional distillation and proportioning the rate of flow of reflux to the rate of flow of product wherein the rate of flow of each can be predetermined and varied as desired.

It is still another object of the invention to provide an improved device for automatically dividing the condensate in fractional distillation into the reflux product and, at the same time, a device for separating water from the condensate and the reflux.

Various other objects and advantages of this invention will become more apparent during the course of the following specification and will be particularly pointed out in the appended claims.

In the accompanying drawing there is shown, for the purpose of illustration, one embodiment which my invention may assume in practice.

In the drawing:

Figure 1 is a plan view of the improved liquid proportioning device of my invention;

Figure 2 is a similar view thereof with the top cover removed therefrom;

Figure 3 is a side elevation of my improved liquid proportioning device, partly in section;

Figure 4 is a section taken on line IV—IV of Figure 1;

Figure 5 is a front elevation of my improved device;

Figure 6 is a section taken on line VI—VI of Figure 4; and

Figure 7 is a section taken on line VII—VII of Figure 2.

Referring more particularly to the drawing, the improved liquid proportioning device of my invention comprises an annular or cylindrical-shaped body member 1 having a plate-like cover 2 arranged thereon. There is arranged centrally of the body member a hollow portion 21 so as to provide an annular chamber 22 therearound.

There is rotatably mounted in the hollow por-

tion 21 on the upper end of a vertically arranged shaft 7, which is arranged through a stuffing box consisting of a packing nut 8 and packing 10 carried by a plate-supporting member 23, and which, in turn, is securely arranged in the hollow portion, a cylindrical cup-like receptacle 3 having a weir 24 arranged in the side thereof adjacent the top of the same. There is arranged with the weir 24 an outwardly and downwardly extending lip portion 25 which extends into the chamber 22 of the body member.

In the chamber 22 of the body member at a point opposite the weir 24 and the lip portion 25 of the receptacle 3 there is positioned a vertically extending dividing plate member 11, having a knife-like upper edge 26. There is also arranged in the chamber, at a point spaced around the same from the dividing plate 11, a vertically extending partition plate 28 so as to divide the chamber into two compartments, one compartment 27 for receiving one part of the liquid or the reflux of the condensate as it is divided, and another compartment 28 for receiving the other part of the liquid or the finished product of the condensate.

There is positioned in the side wall of the chamber in one of the compartments, or the reflux-receiving compartment 27, an outlet 29 for conveying the reflux or divided portion of the liquid from that chamber, and there is similarly arranged in the other, or finished product-receiving, compartment an outlet 30 for conveying the finished product or the other divided portion of the liquid from that compartment.

There is arranged in one compartment of the chamber 22, or the reflux-receiving compartment 27, adjacent the outlet 29 therein, a vertical extending plate member 14 so as to provide a weir over which the liquid or reflux in that compartment is adapted to flow to the outlet 29. There is also positioned in the reflux compartment 27, adjacent the weir 24 and lip portion 25, a vertically extending substantially arcuate-shaped baffle plate 17 around which the liquid or reflux, which is delivered into the compartment 27, is adapted to flow. Immediately in front of the weir or plate member 14 in the bottom wall of the compartment 27 there is arranged preferably an outlet 31 to which one end of a pipe 15 is connected for a purpose hereinafter to be described.

There is suitably mounted adjacent the compartment 28 outside the chamber 22 a cylindrical receptacle or chamber 12 which is connected to the compartment 28 as at 32. The opposite end of the pipe 15 extends up through the bottom of the chamber 12 with the extreme end thereof being positioned at a spaced distance from the bottom thereof intermediate the body of the same, and there is arranged on that end of the pipe 15 an adjustable overflow member 16. There is preferably arranged in the pipe 15 a valve 19 and a drain valve 18.

There is arranged centrally of the plate-like cover 2 a vertically extending cylindrical inlet member 33 which extends into the cup-like receptacle 3 with the bottom end thereof terminating preferably at a point adjacent the bottom of the receptacle and which is adapted to convey the liquid or the condensate to be divided from the source of supply into the receptacle 3.

On the bottom end of the shaft 7 there is mounted a horizontally extending handle member 4 having a vertically extending pointer or indicating member 13 arranged therewith which is adapted to extend upwardly along the outside

of the body member 1. There is arranged preferably on the side wall of the body member, calibrations 34 representing the proportions of the liquid or condensate to be divided, preferably in percent, and with which the pointer 13 is adapted to cooperate. These calibrations preferably represent the percentage of reflux being divided from the condensate. That is, the pointer 13 is adapted to indicate on the calibrations 34 the amount in percent of the reflux being divided from the condensate by the dividing plate member 11 and flowing to the upper side thereof into the reflux-receiving compartment 27.

There is also preferably provided an inspection glass 5 arranged in the cover 2 at a point directly above the dividing plate 11 and a similar inspection glass 6 arranged in the top of the chamber 12 for observing the operation of the device and the action of the liquid as it passes therethrough.

The improved liquid dividing and proportioning device of my invention functions in the following manner. The handle 4 is first manipulated so that the pointer 13 carried thereby is positioned opposite the desired calibration 34 on the outside of the body member 1 so that the weir 24 and the lip 25 of the receptacle 3 associated therewith are positioned properly relative to the liquid dividing plate 11 positioned in the chamber or hollow portion 21. That is, the pointer 13 is positioned so as to obtain the desired portion of the divided liquid or reflux in the compartment 27 and the desired portion of the liquid or finished product in the compartment 28. In the present instance, as shown in the drawing, the pointer 13 and the overflow cup or receptacle 3 are set so that the liquid or condensate will be equally divided, namely, at 50 percent, which will result in one-half the liquid condensate entering the compartment 27, with the other half entering the compartment 28.

The liquid or condensate to be divided and proportioned is then introduced from its source of supply through the inlet member or pipe 33 and into the receptacle 3. The inlet member 33 extends preferably to the bottom of the receptacle so as to prevent surging of the liquid or condensate and to provide an even flow of the same over the weir and the lip portion of the receptacle. It will be understood that the condensate or liquid rises in the receptacle 3 as it is delivered thereto into the level of the weir 24 and then flows over the lip portion 25 and onto the knife edge 26 of the dividing plate member 11. The plate member 11 divides the liquid or condensate as it flows thereover into two portions with one portion, or the reflux, flowing into compartment 27 to one side of the dividing plate 11, and the other portion, or the finished product, flowing to the compartment 28 upon the opposite side of the dividing plate.

The liquid entering the reflux compartment flows from the dividing plate 11 to the partition plate 28 and over the weir 14 and out through the outlet 29. All the liquid entering the reflux compartment will flow substantially the same distance, due to the fact that the baffle plate 17 is positioned opposite the weir and lip portion of the receptacle. That is to say, the reflux is caused to flow around the baffle plate 17 as shown by the arrows in Figure 2 of the drawing. During the flow of the reflux portion of the condensate through the reflux compartment 27, any water therein settles to the bottom of the compartment and is removed therefrom by flowing through the pipe line 15 to the adjustable over-

flow 16 positioned in the chamber 12 and from there flows into the product compartment 28 to be carried away with the finished product. If live steam is not used in the distillation process and it is not necessary to remove water from the reflux compartment, then valve 19 in the pipe 15 may be closed. The portion of the liquid divided or finished product directed to compartment 28 is delivered therefrom through the outlet 30 to the point of delivery. It is preferable that shaft 7 be hollow-drilled so as to permit draining of the receptacle 3 therethrough by removing a plug 9 arranged in the extreme bottom thereof. The compartments in the body member may be drained by opening valve 18 in the pipe 15.

As a result of the present invention, it will be seen that there is provided a simple and inexpensive device for accurately and effectively dividing liquids, or condensate in fractional distillation in which the desired divided proportions can be easily and conveniently determined.

While I have shown and described one specific embodiment of my invention, it will be understood that this embodiment is merely for the purpose of illustration and description and that various other forms may be devised within the scope of my invention, as defined in the appended claims.

I claim:

1. A device of the class described comprising a cylindrical-shaped body member having a hollow central portion with an enclosed chamber arranged therearound, a rotatable cup-like receptacle arranged in the central hollow portion of said body member for initially receiving the liquid to be proportioned, means for delivering the liquid into said receptacle, a weir arranged with said receptacle adjacent the top thereof, a lip portion arranged on the outer side of said weir and said receptacle communicating with the chamber in said body member for directing the liquid thereto, a dividing plate member vertically arranged in the chamber of said body member at a point adjacent the lip portion of said receptacle for dividing the same into two compartments, said dividing plate having a knife-like upper edge with the liquid adapted to flow from said receptacle through said weir and over said lip portion onto said knife-like edge of the dividing plate in the chamber which is adapted to divide the liquid into predetermined proportions with part of the liquid adapted to enter the compartment on one side of the dividing plate and the other part thereof the compartment on the opposite side of the dividing plate, and a vertically disposed baffle plate arranged in one of said compartments at a spaced distance from said hollow central portion and directly opposite the lip portion of the weir of said receptacle whereby the liquid delivered into that compartment flows around said baffle plate so that all of the liquid entering that compartment is caused to flow substantially the same distance.

2. A device of the class described comprising a cylindrical-shaped body member having a hollow central portion with an enclosed chamber arranged therearound, a rotatable cup-like receptacle arranged in the central hollow portion of said body member for initially receiving the liquid to be proportioned, means for delivering the liquid into said receptacle, a weir arranged with said receptacle adjacent the top thereof, a lip portion arranged on the outer side of said weir and said receptacle communicating with the chamber in said body member for directing the

liquid thereto, a dividing plate member vertically arranged in the chamber of said body member at a point adjacent the lip portion of said receptacle for dividing the same into two compartments, said dividing plate having a knife-like upper edge with the liquid adapted to flow from said receptacle through said weir and over said lip portion onto said knife-like edge of the dividing plate in the chamber which is adapted to divide the liquid into predetermined proportions with part of the liquid adapted to enter the compartment on one side of the dividing plate and the other part thereof the compartment on the opposite side of the dividing plate, means for rotating said receptacle relative to said dividing plate member so as to vary the proportion of the liquid flowing from the receptacle into each of the compartments in said chamber, a downwardly extending shaft carried by said receptacle and extending below said body member, a horizontally disposed handle member carried by said shaft for rotating and positioning said receptacle, and a pointer carried by said handle member, said body member having calibrations arranged on the side thereof with which said pointer cooperates to indicate the proportions of the liquid directed by said dividing plate member into the respective compartments of said chamber.

3. A device of the class described comprising a cylindrical-shaped body member having a hollow central portion with an enclosed chamber arranged therearound, a rotatable cup-like receptacle arranged in the hollow central portion of said body member for initially receiving the liquid to be proportioned, means for delivering the liquid into said receptacle, a weir arranged with said receptacle adjacent the top thereof, said chamber being divided into at least two compartments, means associated with said weir for directing the liquid into the chamber of said body from said receptacle, means arranged in the chamber at a point adjacent said last mentioned means which is adapted to divide the liquid into predetermined proportions as it flows thereto from said receptacle with part of the liquid adapted to enter one of the compartments in said chamber and the other part thereof the other of said compartments therein, means for rotating said receptacle so as to vary the proportion of the liquid flowing from the receptacle into each of the compartments in said chamber, a downwardly extending shaft carried by said receptacle and extending below said body member, a horizontally disposed handle member carried by said shaft for rotating and positioning said receptacle, and a pointer carried by said handle member, said body member having calibrations arranged on the side thereof with which said pointer cooperates to indicate the proportions of the liquid directed by said dividing plate member into the respective compartments of said chamber.

4. In the fractional distillation of a liquid, a device for dividing the stream of condensate into the reflux and the finished product comprising a cylindrical-shaped body member having a hollow central portion with an enclosed chamber arranged therearound, a rotatable cup-like receptacle arranged in the hollow portion of said body member for receiving the condensate, a weir arranged with said receptacle adjacent the top thereof, said chamber being divided into at least two compartments, means associated with said weir for directing the

densate into the chamber of said body member, a dividing plate member vertically arranged in the chamber of said body member at a point adjacent said last-mentioned means, said dividing plate having a knife-like upper edge with the condensate adapted to flow from said receptacle over said weir onto said knife-like edge of the dividing plate member which is adapted to divide the condensate into predetermined proportions of reflux and finished product with the reflux adapted to enter one of said compartments in said chamber and the finished product the other of said compartments therein, means for adjusting the position of said receptacle relative to said dividing plate so as to vary the proportion of reflux and finished product entering the respective compartments, means for indicating the proportion of reflux and finished product entering said compartments, an outlet arranged with that compartment into which the reflux is adapted to pass for delivering the reflux therefrom, a weir vertically arranged in said compartment adjacent said outlet over which the reflux is adapted to pass to said outlet, means arranged with said reflux compartment immediately in front of said weir therein for conveying liquid heavier than the reflux liquid therefrom, and an outlet arranged with that compartment into which the finished product is adapted to pass for delivering the finished product therefrom.

5. A device of the class described comprising a cylindrical-shaped body member having a hollow central portion with an enclosed chamber arranged therearound, a rotatable cup-like receptacle arranged in the hollow central portion of said body member for initially receiving the liquid to be proportioned, means for delivering the liquid into said receptacle, a weir arranged with said receptacle adjacent the top thereof, 10 said chamber being divided into at least two compartments, means associated with said weir for directing the liquid into the chamber of said body from said receptacle, means arranged in the chamber at a point adjacent said last mentioned means which is adapted to divide the liquid into predetermined proportions as it flows thereto from said receptacle with part of the liquid adapted to enter one of the compartments in said chamber and the other part thereof the other of said compartments therein, a baffle member arranged in one of the compartments in the chamber adjacent the outlet thereof so as to provide a weir therein over which the liquid delivered thereto is adapted to flow, means arranged in the bottom of said compartment in front of said baffle member therein for directing liquid heavier than the liquid being distilled from said compartment, and an outlet arranged with each of said compartments for conveying the liquid delivered thereto therefrom.

30 ROY P. KEAMMERER.
